CHARLES WESTLEY MORRIS, OF NEWARK, NEW JERSEY.

SHOE-SHINING STAND.

1,127,071.

Specification of Letters Patent.

Patented Feb. 2, 1915.

Application filed July 24, 1913. Serial No. 780,861.

To all whom it may concern:

Be it known that I, CHARLES WESTLEY MORRIS, a citizen of the United States, and resident of the city of Newark, county of 5 Essex, and State of New Jersey, have invented certain new and useful Improvements in Shoe-Shining Stands, of which the following is a specification.

The objects of this invention are to provide in addition to an ordinary container for blackening or shoe polish, a means for imparting to the polish and after it has been applied to a shoe, a high and satisfactory luster. Devices of this kind are generally 15 well-known, but owing to their bulkiness and lack of stability, they have not been fully appreciated. In my invention, I have combined the container and the polisher, so that where one is to be found, there the other will also be, and in doing so, I have not only increased the efficiency of the polisher, and its usefulness, but I have also improved the box or container by providing it with a means that will more surely guard 20 it against accidental overturning, as well as, a more firm base upon which to rest. In my invention, I utilize a well-known polishing means that of a strip of cloth and for the purpose of holding the cloth in an operable position, I provide a means adjustable upon the container, a means that will adjust itself, so that the cloth will bear at the proper angle upon the shoes of varying sizes.

Further advantages and the details of 35 the construction of my device, will be fully set forth as the specification progresses.

The following is what I consider the best means of carrying out this invention and the accompanying drawings form a part of this 40 specification, in which—

Figure 1, is a top plan view of the container with my device collapsed. Fig. 2, is a similar view of the container, but with the arms of the device withdrawn and with 45 a polishing cloth in operable position. Fig. 3, is a bottom plan view of the container showing the arms withdrawn as they will be in operation. Fig. 4, shows a side elevation of the device. Fig. 5, shows a modification 50 in which the cloth holding means alone is used. Fig. 6, shows the device secured to a disk.

Certain advantages of the construction as described in the specification will be found 55 in the modified constructions.

Similar reference numerals indicate like parts in all the figures where they appear.

At 1, I have shown a container for shoe polish or blackening. This container is of ordinary size and construction, being 60 formed with a box portion and a frictionally engaged cover portion adapted to co-operate and serve in the well-known manner. To the bottom of the container, I secure a cleat as shown at 2, the outer ends 3 65 and 4, of which are raised. Under this cleat I pass the inner end of an adjustable cloth holding member, and I so proportion the parts that the cloth holding member may be adjustable through the cleat or through the 70 raised portions 3 and 4, thereof. These cloth holding parts which I may sometimes refer to as arms, are similar in construction, each being formed with a plurality of parallel extension 5 and 6 terminating in short 75 right-angle bends 7 and 8 which are adapted to impinge upon the cleat and to limit the outward motion of the parallel members 5 and 6. The outer ends of the members 5 and 6, I turn outward at right angles to a desired extent, as shown at 9 and 10, and then turn them upward to a certain small extent as shown at 11. I then connect these 80 upward extensions by means of a short arc 12, taking care that each of the arcs 12 will 85 be of the same radius as the adjacent side of the container against which they will under certain conditions impinge.

The polishing cloth or member which is adapted to be used with my device, is shown 90 at 13, and consists of a strip of soft cloth of any desirable length, the ends of which are passed over the box and under the arcs 12.

When it is desired to use my device, the 95 cover of the container is removed and a sufficient quantity of its contents is applied to the shoe. The cover of the container is then replaced and the cloth being in position, the shoe is inserted between the cover of the 100 container and the cloth. The ends of the cloth may then be grasped and with a few rapid motions of the hands upward and downward alternately, the cloth is caused to pass from side to side over the shoe and the desirable high polish is obtained. It 105 will be understood that the cloth may be caused to press upon the shoe with any desirable degree of firmness, and from the construction, it will be seen, that should the 110

shoe be narrow, the cloth holding arms will from the pressure of the cloth be forced inward, thus assuring that the whole upper surface of the shoe will receive the necessary polishing friction.

I desire particularly to call attention to another valuable function of my device, other than its purely mechanical operations. The necessity of replacing the cover upon the box before its use as a polisher insures that the contents of the container will be kept in proper condition, and as the cover of the box usually contains advertising matter, my device prompts the operator to retain the cover, therefore enhancing the value of the advertising matter. In addition to this, the surface of the cloth may be utilized as a medium upon which to imprint additional advertising matter or the instructions as to how to best use the device.

At Fig. 5, I have shown a non-adjustable cloth holding device similar in construction to the device set forth in the earlier figures, but without the container, and at Fig. 6, I have shown an adjustable cloth holding device, secured to a plate or disk, which may contain printed matter of any desirable description. Other modifications may be made. I attach importance however to the construction that allows the arms to slide for the reason as herein set forth, and to the upward projection of the rest as it holds the foot above the plane of the sliding members giving these members a freedom to slide even when a foot is in place thus causing the cloth to impinge on all sides of the shoe. I attach importance to the upward extensions or projections of the arms as they cause the cloth to be retained above the surface of the rest or support upon which my device may be placed and to the round shape

of the rest and the shape of the arms to coincide therewith as they combine to produce a device compact and efficient besides allowing the cloth to follow the shape of the 45 shoe.

Having carefully described my invention, what I claim and desire to secure by Letters Patent, is:

1. A shoe shining stand having a disk and secured thereto a plurality of slidable arms formed of round wire, stops upon the inner ends of each said arm, and a cleat secured to said disk and adapted to retain, guide and limit the outward movement of said 55 arms for the purpose set forth.

2. A shoe shining stand having a disk and in combination therewith a plurality of slidable arms each formed of parallel and outwardly extending wire members, the 60 outer ends of which are joined to produce a transversely and upwardly extending and partly circular loop as and for the purpose set forth.

3. A device of the character described 65 having in combination a disk a plurality of wire members slidably engaged with said disk, a transversely extending and partly circular loop formed in each pair of wire members, a stop formed at the inner end of 70 each said wire member and a cleat for retaining, guiding and limiting the motion of said wire members as and for the purpose set forth.

Signed at Newark, in the county of Essex, 75 and State of New Jersey, this 19th day of July, 1913.

CHARLES WESTLEY MORRIS.
